UNITED STATES PATENT OFFICE.

ROBERT A. STEPS, OF LOS ANGELES, CALIFORNIA.

SCREEN.

1,207,809.

Specification of Letters Patent. Patented Dec. 12, 1916.

Application filed April 11, 1916. Serial No. 90,423.

To all whom it may concern:

Be it known that I, ROBERT A. STEPS, a citizen of the United States of America, residing at Los Angeles, State of California, have invented a new and useful Screen, of which the following is a specification.

The class of screen to which this invention relates is that used in oil or water wells, opposite the petroleum or water strata, for holding back the sands and letting the fluids through. Wells of this character are constructed of heavy pipe, in 20' lengths, a sufficient number of such lengths being screwed together to reach from the surface 15 of the ground to the bottom of the well. The portion of the pipe that is set in the producing strata, is perforated so as to form a screen for letting the fluids in.

One of the objects of this invention is to 20 increase the capacity or productivity of such screens, and particularly of the so-called integral screens, that is screens having neither wire, buttons, nor other removable parts, but having the straining apertures formed integrally in the body of the pipe. And I accomplish this chiefly by 25 forming lateral feeders in the outer surface of the body of the pipe adjacent and tributary to the longitudinal main straining 30 apertures so that the surface of the pipe in this vicinity is like a grate holding the sands off from the body of the pipe so that underecurrents of oil may flow in the space below the sands and in the feeders laterally 35 toward the main apertures, through which the oil enters the well. The oil is then pumped to the surface by suitable pumps inserted in the well.

The drawings illustrate what I consider 40 the best form of the invention.

Figure 1 illustrates in section, a piece of pipe with suitable main apertures therein. No effort is made to show the lateral feeders in this figure. For convenience, however, 45 the roller for arching the apertures is shown diagrammatically from the front and side. Fig. 2 is a diagrammatic illustration, from the side and front, of a convenient tool for forming the lateral feeders. Fig. 3 is a 50 highly magnified view showing the surface of the pipe in the vicinity of the longitudi-

nal main apertures after the lateral feeders have been formed therein. This represents a small fragment of the finished screen. Fig. 4 is a longitudinal section taken midway through the slit looking in the direction of the arrows x^4-x^4 . Some of the sand is shown in this figure so as to indicate the grate-like action of the lateral feeders. Fig. 5 is a diagrammatic view showing a portion 60 of a length of pipe finished into screen in accordance with my invention.

Referring to Fig. 1, the pipe 1 is shown as equipped with longitudinal apertures 2, which I term "main apertures," because 65 they are the main channels penetrating the walls of the pipe and letting the oils or water through from the sands. These apertures may of course be of any suitable form and shape but I prefer that they should be elongated, as shown in Figs. 3 and 5, and of arched construction as in Fig. 1, the slit being narrower on the outside than on the inside, and I consider elongated apertures, 70 of any form, specially advantageous.

The apertures 2, Fig. 1, are produced by my special method, forming the basis of a separate application filed April 11, 1916, Serial Number 90,422. They are first formed of uniform width throughout, and 80 are then arched over by displacing the outside adjacent metal inward. For this latter purpose I use some suitable tool, such as the roller 3, Fig. 1, and by applying pressure to this roller, and rolling it back and forth along the length of the slit, the apertures become arched as shown, and the side ducts 4, Figs. 1, 3, and 5, paralleling the main aperture, are formed at the same time. The 85 way in which these ducts participate in the general function of the screen will be illustrated later on.

Referring now to the lateral feeders, these can be best understood from Figs. 3 and 4, 90 from which it will be observed that these feeders consist chiefly of the depressions 95 formed in the outer surface of the pipe adjacent the main apertures 2. In my judgment it is sufficient for these feeders to extend only a short distance, say three quarters of an inch, or one inch, on either side of the slits 2, because beyond this point 100

their influence and efficiency seem to drop off. However, if desired, these feeders or depressions may be extended much farther, and may even encircle the entire pipe. I content myself however, by forming them only in the locality of the aperture 2 to which they are tributary, see Figs. 3 and 5, and for producing them in this form I use a suitable nurling tool 6, Fig. 2. This tool, like the roller 3, is of course made of hardened tool steel, and as indicated, is equipped with sharp teeth 7 around its entire periphery. By rolling such a tool back and forth, under pressure, and over the slit or aperture 2, the depressions or feeders 5, Fig. 3, are of course formed, the process being that of the well known nurling of such contours into the surface of metals. Of course the feeders can be formed in other ways, as by use of a cold chisel, or by a properly formed die covering the entire knurled area shown in Fig. 3, in which case all the feeders may be punched or hammered in at one time without any rolling action, but the method of forming the feeders is of course immaterial in this application, except to show that they can be made on a good practical commercial basis. Screens having these side feeders produce more oil or water from a given stratum than screens that have no feeders.

Whether the feeders are present or absent, the sands and gravels will of course pack onto the surface of the pipe, and will cover the space at the slit, the particles of gravel resting firmly on the edges of the latter. Therefore, if the side feeders are absent, the oils can enter the slit only through the voids remaining between the particles of gravel and the edges of the slit, and probably the oil approaches the slit chiefly by percolating toward it from the front. In all likelihood however, there is little side or lateral flow toward the slit,—i. e. in the absence of side feeders,—and it is by effectively opening up these lateral currents that the screen herein disclosed attains its superiority.

As shown in Fig. 4, the V shaped depressions 5 hold the sands 5' off the body of the pipe. These sands, being comparatively coarse, cannot squeeze into the base 5" of the depressions, so that a more or less unobstructed channel is formed by the base or root 5" of the feeders through which the oil may flow laterally toward and into the slit 2. The ducts 4 also help by forming reservoirs, so to speak, in the vicinity of the slits, so as to especially soak the sands at the slit, and in addition, since these ducts also extend beyond the ends of the slits, see Fig. 3, they serve to conduct the oil from the extreme upper and lower feeders 8, beyond the ends of slits 2, down to and opposite the slits to where the oil can gain ready entrance. In this way the sands are drained much more thoroughly, in view of the assistance given by the side flows. The tendency of these side flows is to cumulate their effect with that of the front flow, and of course, since the feeders open directly into the slits, the receiving capacity of the latter is increased so that the side flows are free to spill their oils into the slit without encroaching upon the passages through which the front flows enter. For these reasons the establishing of the side flows does not reduce or minimize the front flows, but both go on independent of each other, and the producing capacity of the screen is increased just that much. Also, as indicated in Fig. 3, pressing the feeders 5 into the body of the metal, produces a beaded effect 9 along the edge of the slit. If deemed advisable these beads may of course be removed by the insertion of a cleaning tool, but I consider the beaded edge advantageous and consider its removal as detrimental to the best interests of the screen. The effect of the beading is as follows: The crest of the beads holds out the finer sands, so that a narrow mesh screen is virtually produced, whereas, in view of the bulges in the beads, the increased capacity of a wider mesh screen is obtained, and therefore, to a greater or less degree, there is coupled in one and the same slit the straining advantages of a fine slit, with the higher capacity features of a coarser slit. The advantage from this source is of course obvious. Also, it will be understood that the lateral feeders need not extend out exactly at right angles to the main apertures 2. As shown in the row of slits marked 10, Fig. 5, these feeders may extend at various inclinations, and two or more sets of crossed feeders may even be impressed over each other as at 11, in which event the metal will be so chafed that the lateral feeders will have no single well defined course but may be traced around many courses around the projections left in the metal. Also, as previously indicated in the foregoing description, the troughs or reservoirs 4, Fig. 1, either on one side or on both sides of the apertures, especially in connection with the inward flare of the material between the troughs and the edges of the apertures, are a great advantage because the pronounced inwardly flaring lips thus formed at the outside edge of the slits, see Fig. 1, being relieved, so to speak, on all sides, tend to dig out vigorously into the sands and are the better able, on this account, "to get" the oil or water which they are seeking, and in view of the adjacent parallel troughs helping to hold the sands loosely off the pipe at that point and forming reservoirs or basins for the collection of pools of oil there, the production or flow of oil into slits of this gen-

eral configuration is especially efficient and constitutes an important feature of the invention. The viscosity of the oil as it passes into the aperture seems to help in drawing more oil from the adjacent troughs 4. Of course all this is true whether the lateral feeders are present or not, and, although I prefer to finish the pipe with the lateral feeders, yet it will be obvious that my screen as shown in Fig. 1, and in the uppermost row of apertures, just at the fracture of the pipe, Fig. 5, just before the lateral feeders are formed therein, constitutes a very good screen in itself regardless as to whether the lateral feeders are added or not. Also, in my screen, it will be apparent that the apertures and troughs are unobstructed outwardly so that the well sands can lie directly upon and feed directly into the apertures. In other words my apertures are the main screening apertures, and are not merely supplementary apertures through the pipe with a covering of wires or buttons or other members through which the real screening is done. My construction therefore couples simplicity and directness with efficiency, without sacrificing any desirable feature. Also, I count it an advantage with my screen that it is substantially smooth both inside and outside by which I mean that all features are reasonably within the ordinary cylindrical surfaces of the pipe. As compared with other common serrated or punched pipe, it will be noted that the plain surface of the pipe on one side of my slit is substantially a continuation of the plain surface of the pipe on the other side of the slit, which is not the case in serrated pipe where the principle of manufacturing is such that the metal on one side of the slit is punched in or out past the metal on the other side of the slit. In this case it cannot be said that the plain surface on one side is substantially a continuation of the plain surface of the metal on the other side of the slit, because just the reverse is true, and in this respect I deem my arrangement very advantageous because the serrations in perforated pipe stick out like spears or saw teeth and either bite into the sands so as to prevent shoving or pulling the screen into place, if the serrations are driven to the outside, or else, if driven toward the inside, they interfere with finishing tools, bailing tools, and other devices that must frequently be lowered into the well for cleaning it.

I claim:

1. A well screen for working in oil or water well sands, consisting of pipe the walls of which are equipped with elongated apertures extending therethrough so that fluids can pass through said apertures from the outside to the inside of said pipe, and depressions formed in the outside surface of the body of the pipe and extending away

laterally from said apertures so as to form feeders for conducting undercurrents along said pipe toward said apertures, the apertures being unobstructed outwardly so that the well sands can lie directly upon and feed directly into the said apertures, and the plain surface of the metal on one side of the apertures being substantially a continuation of the plain surface of the metal on the other side of the apertures. 75

2. A well screen for working in oil or water well sands, consisting of pipe the walls of which are equipped with elongated apertures extending therethrough so that fluids can pass through said apertures from the outside to the inside of said pipe, and depressions formed in the outside surface of the body of the pipe and extending away laterally from both sides of said apertures so as to form feeders for conducting undercurrents along said pipe toward said apertures, the apertures being unobstructed outwardly so that the well sands can lie directly upon and feed directly into the said apertures, and the plain surface of the metal on the one side of the apertures being substantially a continuation of the plain surface of the metal on the other side of the apertures. 85

3. A well screen for working in oil or water well sands, consisting of pipe the walls of which are equipped with elongated apertures extending therethrough so that fluids can pass from the outside of the pipe to the inside, said apertures being narrower toward the outside of the pipe than toward the inside, and lateral feeders formed in the outside surface of the body of the pipe and extending away laterally a limited distance from said apertures for producing lateral undercurrents along the pipe toward the apertures said apertures being unobstructed outwardly so that the well sands can lie directly upon and feed directly into the apertures, and the plain surface of the metal on one side of the apertures being substantially a continuation of the plain surface of the metal on the other side of the apertures. 100

4. A well screen for working in oil or water well sands, consisting of pipe, the walls of which are equipped with elongated apertures extending therethrough so that fluids can pass through said apertures from the outside to the inside of the pipe, and reservoirs or troughs beside the apertures and parallel thereto, each trough comprising a depression in the outside surface of the pipe alongside an edge of the aperture and parallel thereto, the relatively small amount of material between the trough and the adjacent edge of the aperture being flared inward toward the aperture so as to make the aperture narrower near the outside of the pipe than near the inside of the pipe, the said apertures and troughs being unobstructed 115 120 125 130

ed outwardly so that the well sands can lie directly upon and feed directly into the said apertures, and the plain surface of the pipe on one side of the aperture being substantially a continuation of the plain surface of the pipe on the other side of the aperture.

In testimony whereof, I have hereunto

set my hand at Los Angeles, California, this 4th day of April, 1916.

ROBERT A. STEPS.

In the presence of—

ROBERT T. WILLIAMS,
J. H. DECIUS.
